CLAIM

The ornamental design for a marine animal toy set as shown and described.

DESCRIPTION

FIG. 1 is a perspective view of a marine animal toy set; FIG. 2 is a perspective view of a first piece of the marine animal toy set;

FIG. 3 is another perspective view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a top plan view thereof;

FIG. 9 is a bottom plan view thereof;

FIG. 10 is a perspective view of a second piece of the marine animal toy set;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a perspective view of a third piece of the marine animal toy set;

FIG. 18 is a front elevation view thereof;

FIG. 19 is a rear elevation view thereof;

FIG. 20 is a left side elevation view thereof;

FIG. 21 is a right side elevation view thereof;

FIG. 22 is a top plan view thereof;

FIG. 23 is a bottom plan view thereof;

FIG. 24 is a perspective view of a fourth piece of the marine animal toy set;

FIG. 25 is another perspective view thereof;

FIG. 26 is a front elevation view thereof;

FIG. 27 is a rear elevation view thereof;

FIG. 28 is a left side elevation view thereof;

FIG. 29 is a right side elevation view thereof;

FIG. 30 is a top plan view thereof;

FIG. 31 is a bottom plan view thereof;

FIG. 32 is a perspective view of a fifth piece of the marine animal toy set;

FIG. 33 is another perspective view thereof;

FIG. 34 is a front elevation view thereof;

FIG. 35 is a rear elevation view thereof;

FIG. 36 is a left side elevation view thereof;

FIG. 37 is a right side elevation view thereof;

FIG. 38 is a top plan view thereof;

FIG. 39 is a bottom plan view thereof;

FIG. 40 is a perspective view of a sixth piece of the marine animal toy set;

FIG. 41 is another perspective view thereof;

FIG. 42 is a front elevation view thereof;

FIG. 43 is a rear elevation view thereof;

FIG. 44 is a left side elevation view thereof;

(Continued)

FIG. 45 is a right side elevation view thereof;
 FIG. 46 is a top plan view thereof;
 FIG. 47 is a bottom plan view thereof;
 FIG. 48 is a perspective view of a seventh piece of the marine animal toy set;
 FIG. 49 is another perspective view thereof;
 FIG. 50 is a front elevation view thereof;
 FIG. 51 is a rear elevation view thereof;
 FIG. 52 is a left side elevation view thereof;
 FIG. 53 is a right side elevation view thereof;
 FIG. 54 is a top plan view thereof; and,
 FIG. 55 is a bottom plan view thereof.

The broken lines in the drawings depict portions of the marine animal toy set that form no part of the claimed design.
